WEFT CUTTER ON MULTISHUTTLE
BOX LOOMS

Charles Fiorina, Hawthorne, N. J., assignor of
sixty-five per cent to Infall Novelty Company,
Paterson, N. J., a corporation of New Jersey

Application January 25, 1945, Serial No. 574,511

5 Claims. (Cl. 139—291)

1

A type of loom is known in which, beside and spaced from usually each margin of the warp proper and subject to shedding and advance therewith, a so-called "catch-cord" (otherwise herein termed an auxiliary warp element) is present around which the filling or weft is trained after the manner of forming the conventional selvage. Said catch-cord is spaced as indicated so that on severing the filling between it and the warp proper at a suitable distance from the latter's margin a fringe will be left on so much of the piece as is formed by the filling and warp proper, or what may be termed a woven band. Having produced the fringed band it may be severed transversely to form kerchiefs or the like.

Frequently, in order to produce a band providing repeated given patterns a plurality of kinds (as colors) of filling are used, usually so that one of the fillings will develop a woven zone of maximum width, and such being the case, and if the loom had a filling or weft stop-motion means, the severing has had to be done by hand after a considerable length of the goods has been completed and removed from the loom, such involving great waste of time and labor and requiring considerable skill in the effort to sever with precision or in true parallelism with the margin of the interwoven warp proper and filling.

By the present invention, as considerable practice has shown, the longitudinal severing is effected by means active during the weaving. The construction is such that the mentioned stop-motion means goes into action only as and when intended, or only when the filling from any shuttle at any time in action is broken or fails as to tension and in no instance as an incident of disruption by the severing means.

In the drawings,

Fig. 1 is a side elevation of a standard loom made to embody my invention;

Fig. 2 is an isometric diagram showing the position of the severing means relatively to the piece being produced;

Fig. 3 is a side elevation of a conventional weft-stop motion, the batten and breast-beam appearing in section; and

Figs. 4 and 5 are front and side elevations, respectively, of the severing means and associated guide.

Supporting structure 1 includes the breast-beams 2.

What I term the warp includes the warp proper *a* and a flexible catch-cord or auxiliary

warp element *b*. Such warp is assumed to be supplied, under tension, by any well-known let-off means 3 and to be advanced by any well-known take-up means comprising the usual sand-roller 4 to be driven at constant rate, through gearing 5, from a ratchet-wheel 6 driven by a pawl 7 connected with the batten structure 8, including batten 8a (Fig. 3) and which in turn is reciprocated from the crank-shaft 9 of the loom by pitmen, as 10. This is the picker-stick for throwing the shuttles, being actuated by any conventional means. Usually there will be other groups of warp proper, as *a'*, and the groups will be spaced as shown for the simultaneous development of separate woven bands; and usually, besides the auxiliary warp-element *b*, here at the left, there will be a complementary one at the right of the group or groups of warp proper present.

The shuttles 12 and 13 (only two being here shown) are to be delivered from boxes (Fig. 2) of a box-set 14 to be raised or lowered to bring into line with the batten one or the other of the shuttles. For effecting such movement of the box-set any conventional means (as in the Wattie Patents Nos. 551,104 and 585,607) may be used, to wit, including a floating lever 15 connected with the box-set lifting rod 16, links 17 connecting the lever with cranks 18 fulcrumed in structure 1, connectors 19 connecting the cranks with vibrator gears 20, gears 21 for rotating the vibrator gears, means for rotating the gears 21 constantly from the crank-shaft including gears 22, vibrator levers 23 and any constantly driven pattern-controlled means (not shown) but see Wattie, *supra*, No. 585,607, for instance) 23a for raising and lowering the levers 23 and including the link 23b.

The warp-shedding means, comprising harness shafts 24, is shown in Fig. 1, how it is operated, as by any well known means so as to reciprocate the harness shafts in opposite directions, is not here material.

In Figs. 1 and 3 is shown a conventional filling stop-motion means (see Patent No. 376,774, for instance). A feeler 25 pivoted on the batten normally falls thus to act through a rod 26 to lift the dagger 27 into position to engage the notch 28a of a lever 28 journaled in structure 1 for stopping the loom. A rod 29 pivoted in said structure acts through the dagger and rod 26 to lift the feeler to permit passage of a shuttle when the batten is back but to permit the feeler to fall when the batten moves forward; if there is tensioned filling under the feeler on the for-

ward stroke of the batten the dagger is allowed by the feeler to fall to clear said notch, but if such filling is absent the dagger is lifted and engages the notch to effect stopping of the loom.

What has so far been described is conventional in looms of the type first hereinbefore referred to adapted for weaving with the use of catch-cords, as *b*, and with the use of a plurality of shuttles and having a filling stop-motion means.

As the weaving proceeds the shuttles go into action as determined by the means controlling the vibrator levers 23—here alternately because in this example there are only two shuttles shown, though the number of shuttles partaking in the weaving is not material so long as there are at least two. If the filling from either shuttle fails, as by being exhausted, the weft stop-motion means will stop the loom on the ensuing flight of the shuttle. It will be understood that since the catch-cord *b* is subject to shedding the same as the warp proper the filling becomes trained around it to form what is in effect a selvage.

Now my invention is particularly related to the weaving of repeated patterns in each of which, a plurality of shuttles being used to develop each pattern, one shuttle continues in action while the warp is being advanced through a maximum distance whereby that shuttle lays filling in the warp sheds to form a woven zone of maximum width, which I term the wider zone. The continuous filling so laid through the sheds I term the primary filling. What I term the primary zones thus formed will in the finished piece be spaced from each other and have (extending from one to the other margin of the piece) their final filling stretches all equally spaced apart. In the space between each two such zones another shuttle or shuttles go into action, perhaps, also, together with the first-named shuttle, each to lay continuous secondary filling in the sheds for the forming of another or other zones, which I term the narrower zone, and which has a width less than that of the wider zone.

So much of the loom as includes the shuttles (here only two), the picker-stick, box-set and the means for shifting the latter to bring a given shuttle in line with the lay I treat as means, while the warp is advanced at constant rate and subjected to shedding, for performing two functions, to wit, (1) laying continuous filling *d* through the warp sheds to form with the warp, spaced from each other lengthwise of the warp, woven primary zones *y* all having their final stretches equally spaced apart and (2) laying continuous filling *c* through the sheds in the spaces *x* between said zones to form other and narrower woven zones. Shuttle 12 provides the filling *c* for the woven zones *x* and shuttle 13 provides the filling *d* to form the woven zones in the spaces *y*.

Now, in bearings 30 on structure 1 is journaled a shaft 31 geared at 32 with the gearing 5 so as to be rotated clockwise as viewed from the right in Fig. 2. This shaft has fast thereon a disk-shaped cutter 33 having its periphery as its cutting edge, it being arranged in a plane between the catch-cord *b* and the adjoining warp-proper *a* and projecting through the plane of the intervening filling; since there are here shown two groups of warps proper there is a similar cutter 33a on the shaft similarly located with respect to such groups. As the severing proceeds these cutters sever the filling as they rotate thus to form a fringe on each band of fabric developed.

As for the cutters 33a which sever between the groups of warp proper the same might be placed anywhere lengthwise of the already woven area, but this is not true of cutter 33 which severs between the catch-cord and adjoining warp proper. Thus account must be taken of the circumstance that cutter 33 may be active to sever the filling extending from such a shuttle, as 12, Fig. 2, which is inactive, or remaining boxed, 10 while the other shuttle is active, with the consequence that when the former shuttle again goes into action the weft stop-motion would cause stopping of the loom because its severed filling would not depress the feeler.

Hence, according to my invention I position the cutters (especially cutter 33) completely forward of the last wider zone adjacent the fell which has just been completely woven. The final filling stretches of the zones *y* being all equally spaced apart it follows that, with the cutter 33 so positioned, such cutter cannot sever until the filling from shuttle 12 has first been more or less laid in the warp sheds and so has passed the feeler and held it depressed. The cutter is here so far forward as to be below the breast-beam, 25 but I do not wish thus to be limited. In the spaces *y* the zones woven or left unwoven are wider than the zones *x*.

Said shaft for the cutters is preferably arranged below the breast-beam, between it and the sand-roller, being forward of the depending part of the piece. Since the cutters rotate clockwise (viewed from the right, Fig. 2), or so that their peripheral portions which are between the shaft and the warp move generally in the same direction as the latter, and of course at a different speed, the filling is assuredly severed, especially in view of the following: A guide 34 is attached to and depends from the breast-beam back 40 of and so as to be wiped by the piece and it is slotted at 34a to accommodate the corresponding cutter.

That one of said guides which cooperates with the cutter 33 has one arm thereof, i. e., the arm 45 34b adjoining the catch-cord, bent forwardly thus to form an abutment suitably spaced from the cutter. Although the warp is of course advanced under tension by what I term "going means" comprising the take-up and let-off means, the 50 catch-cord, under the tension of the filling, usually bows inwardly to an extent which, in the absence of said abutment, would result (as considerable practice has shown) in its being severed by the cutter.

55 Said abutment, therefore, serves to hold the catch-cord from bowing inwardly into the path of the cutter.

Having thus fully described my invention, what I claim is:

60 1. A loom including supporting structure, means to advance, at constant rate and in synchrony, a warp proper and a flexible auxiliary warp-element spaced from and paralleling a margin of the warp proper and forming with the latter the warp of the fabric to be woven, means for repeatedly forming sheds in the warp during advance thereof, means to lay continuous primary filling through the sheds and form with the warp, spaced from each other lengthwise of the warp, woven wider zones all having their final filling stretches equally spaced apart by spaces narrower than said zones, means to lay continuous secondary filling through the sheds in the spaces between said wider zones and form other narrower woven zones, means to indicate filling

failure each time filling is laid through a shed, and a cutter on said structure arranged to sever the filling portions connecting the warp proper and auxiliary warp element, said cutter being positioned completely forward of the last wider zone adjacent the fell, which has just been completely woven, a sufficient distance so that the filling from the second named filling laying means remains intact until said last named means has laid at least the initial filling through the sheds forming a part of the next succeeding narrower zone.

2. A loom including supporting structure, means to advance, at constant rate and in synchrony, groups of warp proper paralleling and spaced from each other and a flexible auxiliary element spaced from and paralleling the relatively outer margin of one such group, such groups and element forming the warp of the fabric to be woven, means for repeatedly forming sheds in the warp during advance thereof, means to lay continuous primary filling through the sheds and form with the warp, spaced from each other lengthwise of the warp, woven wider zones all having their final filling stretches equally spaced apart, means to lay continuous secondary filling through the sheds in the spaces between said wider zones and form other narrower woven zones, means to indicate filling failure each time filling is laid through a shed, a shaft supported by said structure and extending transversely of the warp, and cutters on the shaft respectively arranged to sever the filling between said groups and between said element and the adjoining group, said shaft and cutters being positioned completely forward of the last group of wider zones adjacent the fell, which has just been completely woven, a sufficient distance so that the filling from the second named filling laying means remains intact until said last named means has laid at least the initial filling through the sheds forming a part of the next succeeding narrower zone.

3. In a loom, the combination of supporting structure including a breast-beam, a rotary shaft journaled in said structure below and parallel with the breast-beam and having in fast relation to itself a cutter having a peripheral cutting edge and projecting through the plane of the warp extending over the breast-beam and downwardly, and a guide for the warp depending from the 50

breast-beam at the breast-beam side of the warp and having a slit receiving the peripheral portion of the cutter.

4. In a loom, the combination of supporting structure having a breast-beam, going means in said structure including means for advancing under tension warp having filling interwoven therewith, a rotary shaft journaled in said structure below and parallel with the breast-beam and having in fast relation to itself a cutter having a peripheral cutting edge and projecting through the plane of the warp extending from the breast-beam downwardly, means, driven by said going means, to rotate said shaft in the direction in which that peripheral portion of the cutter which adjoins the warp moves downwardly, and a guide for the warp depending from the breast-beam rearward of the warp and having a slit receiving the peripheral portion of the cutter.
5. In a loom, the combination of supporting structure, means therein for advancing under tension a warp proper and a flexible auxiliary warp element paralleling and spaced from a margin of the warp proper, said warp proper having filling interwoven therewith and trained around said element, severing means on said structure including a cutter projecting into the path of the part of the filling between the warp proper and said element, and means on said structure 20 wiped by said element and holding the same clear of the cutter.
